UNITED STATES PATENT OFFICE.

WILLIAM LÜCKE, OF PHILADELPHIA, PENNSYLVANIA, ASSIGNOR TO M. W. LIPPER & CO., OF SAME PLACE.

DESIGN FOR SUSPENDER-WEBBING.

SPECIFICATION forming part of Design No. 23,712, dated October 23, 1894.

Application filed August 10, 1894. Serial No. 519,995. Term of patent 3½ years.

To all whom it may concern:

Be it known that I, WILLIAM LÜCKE, a citizen of the United States, residing at Philadelphia, in the county of Philadelphia and State 5 of Pennsylvania, have invented a new and original Design for Suspender-Webbing, of which the following is a specification.

The leading feature of my design for suspender webbing is the meshing of warp and 10 cords forming a solid band.

In the drawing A designates the warp or stay, B designating the cord forming the mesh or plaiting.

I claim—

The design for a suspender webbing substantially as shown and described.

WILLIAM LÜCKE.
